[57] CLAIM

The ornamental design for a combined bottle and cap, substantially as shown and described.

DESCRIPTION

FIG. 1 is a perspective view of a combined bottle and cap showing our new design;

FIG. 2 is a side elevational view, the opposite side being substantially a mirror image thereof;

FIG. 3 is a view looking from the left of FIG. 2;

FIG. 4 is a view looking from the right of FIG. 2;

FIG. 5 is a top plan view;

FIG. 6 is a bottom plan view; and

FIG. 7 is a cross-sectional view taken on the line 7—7 of FIG. 2;

FIG. 8 is a perspective view showing a modified form of our new design;

FIG. 9 is a side elevational view, the opposite side being substantially a mirror image thereof;

FIG. 10 is a view looking from the left of FIG. 9;

FIG. 11 is a view looking from the right of FIG. 9;

FIG. 12 is a top plan view;

FIG. 13 is a bottom plan view; and

FIG. 14 is a cross-sectional view taken on the line 14—14 of FIG. 9.
